UNITED STATES PATENT OFFICE.

GEORGE H. DORGELOH, OF SCHENECTADY, NEW YORK, ASSIGNOR TO GENERAL ELECTRIC COMPANY, A CORPORATION OF NEW YORK.

RHEOSTAT.

941,441.

Specification of Letters Patent. Patented Nov. 30, 1909.

Application filed June 10, 1908. Serial No. 437,753.

To all whom it may concern:

Be it known that I, GEORGE H. DORGELOH, a subject of the Emperor of Germany, residing at Schenectady, county of Schenectady, State of New York, have invented certain new and useful Improvements in Rheostats, of which the following is a specification.

This invention relates to means for controlling electric motor circuits and has for its object the provision of a device of this character whereby a motor may be brought up to running speed in a reliable and efficient manner and at the same time is free from danger of injury by abnormal conditions of the circuit or carelessness of the operator.

In carrying out my invention I provide in connection with a starting resistance, an unbiased controlling arm, that is one which may be left upon any of the starting contacts. This controlling arm is so interlocked with an automatic circuit-breaker that the latter cannot be closed until the arm is moved to starting position. The underload coil of the circuit-breaker is controlled by the starting arm independently of the movement of the arm over the starting contacts, that is the handle of the controlling arm must be held in a definite position in order to energize the underload coil and keep the circuit-breaker closed. If the operator should release the handle on any intermediate contact the underload coil will be de-energized and the circuit will be opened. In order to maintain the circuit-breaker closed when the controlling arm is in running position I provide a latch which cooperates with the arm to control the underload coil. The arm is provided with a short-circuiting brush which co-operates with stationary contacts to short-circuit the controlling arm when the running position is reached and the latch is arranged so as to grasp the arm and firmly hold the brush against the contacts.

Other objects of my invention will appear in the course of the following specification in which I have shown the invention embodied in concrete mechanism for purposes of illustration.

In the drawings, Figure 1 represents a plan view of the rheostat embodying my

invention; Fig. 2 represents a sectional view of the same; Fig. 3 shows a detail of the latching mechanism for the arm; Fig. 4 shows the interlocking mechanism between the arm and the circuit-breaker; and Fig. 5 is a diagram of the circuits.

Referring to the drawings 10 is a base or panel-board of some insulating material, such as slate or soapstone, having mounted thereon in an arc of a circle a plurality of contacts 11 forming terminals for the starting resistance 12. These contacts are arranged to be engaged by contact strips forming a clip 13 mounted upon the underside of the controlling arm 14. This arm is pivoted at 15 and is unbiased so that it may be left upon any of the contacts as desired. An automatic circuit breaker 16 is mounted upon the panel-board adjacent to the first of the starting contacts. This circuit-breaker is of a standard type and forms no part of my invention. The particular type of circuit-breaker I prefer to use is the double-pole type having the arms arranged for independent movement. The starting rheostat and the circuit-breaker are so interlocked that the latter cannot be closed until the controlling arm is moved to starting position. The arrangement whereby this object is attained is described and claimed in the patent to Yates and Fenwick No. 793,493. Generally speaking the circuit-breaker is prevented from closing by a spring-pressed pin 17 which projects upward through the base so as to engage one arm of the circuit-breaker and prevent its closing. A rod 18 is mounted beneath the panel so as to slide longitudinally and is provided with an opening 19 through which the pin 17 may be forced when the rod is moved so as to make the opening register with the pin. This movement of the rod is effected by a member 20 projecting through the panel into the path of the controlling arm so that the arm may force it in one direction while a spring 21 will return to the position shown in Fig. 4. The underload coil 22 of the circuit-breaker having a resistance R in series therewith has one end connected with a contact segment 23 while the other end is connected with one of the circuit-breaker contacts. This segment is arranged to be engaged by a contact finger 24 pivoted upon

the arm 14 so as to move at right angles thereto. The handle 25 has an extension 26 which passes through the arm so as to give it a swiveling motion. The finger 24 is mounted upon this projection and a spring 27 holds the handle in the position shown in Fig. 2 so that the finger 24 is normally out of contact with the segment 23. By twisting the handle, however, the finger may be brought into contact with the segment and the contact will immediately be broken when the handle releases. A laminated contact brush 28 is mounted upon the arm 14 so as to engage the fixed contacts 29 when the arm is in the running position. In order to press the brush, which is slightly yielding, into firm engagement with the contacts, I provide a latch 30 pivoted upon the base in bracket 31. This latch is normally spring-pressed so that its hook or engaging portion is forced upward. When the arm is forced over the latch and the brush is firmly pressed against the contacts, the arm will be automatically latched in position shown in Fig. 3. In order to make it possible to release the handle when the arm is in running position and still maintain the circuit with the underload coil closed I connect the latch with the underload coil so that the circuit of the coil may be closed between the bracket upon which the latter is mounted and the arm. This likewise assures the opening of the circuit-breaker when the arm leaves running position.

The arrangement of circuits and mode of operation are as follows: In order to start the motor, the arm is first brought to the starting position so that the circuit-breaker may be closed. The operator then grasps the handle and by turning it in a clockwise direction upon the arm, contact is made between the segment 23 and finger 24 so that the no-voltage coil 22 is energized from the positive main to segment 23, finger 24 to the pivot 15 and back to the negative main through the other arm of the circuit-breaker. The circuit-breaker is thus kept closed while the operator moves the arm to the running position. If, however, he should carelessly leave the arm in any of the intermediate positions so as to endanger the resistance, the underload coil will immediately be de-energized. It will then be necessary to return the arm to starting position before the circuit can be closed. If the arm is moved to running position, it is latched there and the brush 28 is held in firm engagement with the contacts 29. In this position the handle may be released without deenergizing coil 22 since the latter is now energized from the segment 23 through conductor 32 and arm 14. If the circuit breaker should open by reason of normal conditions on the circuit the arm must be returned to starting position before the circuit can be again closed.

By this arrangement the controlling arm is normally held in running position and will not be moved by jarring or by accidentally striking it since it must be positively released from the latch. The armature circuit is also closed independently of the starting contacts and the short-circuiting switch is pressed into firm engagement with the contacts so as to make a firm and efficient contact.

While I have described my invention in connection with certain specific structural features and arrangement of circuits, it should be understood that I do not limit my invention thereto except in so far as it is limited by the scope of the claims annexed hereto.

What I claim as new and desire to secure by Letters Patent of the United States, is:

1. A controlling device for electric motors comprising a starting resistance, an unbiased controlling arm therefor, a switch in connection therewith for short-circuiting the arm when the latter reaches running position, and a latch for holding the switch firmly closed.

2. A controlling device for electric motors comprising a starting resistance, an unbiased controlling arm therefor, an automatic circuit-breaker controlled by said arm, a switch in connection with the arm for short-circuiting the same when it reaches running position, and a latch for controlling the circuit-breaker and holding the switch firmly closed.

3. A controlling device for electric motors comprising a starting resistance, an unbiased controlling arm therefor, a yielding switch having one member connected to said arm for short-circuiting the latter when it reaches running position, and a latch for holding the switch member firmly in contact.

4. A controlling device for electric motors comprising a starting resistance, an unbiased controlling arm therefor, an automatic circuit-breaker having an underload coil controlled by said arm, a switch in connection with the arm for short-circuiting the same when it reaches running position and a latch for controlling the underload coil and holding the switch firmly closed.

5. A controlling device for electric motors comprising a starting resistance, an unbiased controlling arm therefor, an automatic circuit-breaker controlled by said arm, means for preventing the closing of the circuit-breaker until the arm is moved to starting position, a switch in connection with the arm for short-circuiting the same when it reaches running position, and a latch for controlling the circuit-breaker and holding the switch firmly closed.

6. A controlling device for electric motors comprising a starting resistance, an un-

biased controlling arm therefor, an automatic circuit-breaker having an underload coil controlled by said arm, means for preventing the closing of the circuit-breaker until the arm is moved to starting position, a switch in connection with the arm for short-circuiting the same when it reaches running position, and a latch for controlling

the underload coil and holding the same firmly closed. 10

In witness whereof, I have hereunto set my hand this 9th day of June, 1908.

GEORGE H. DORGELOH.
